PROCESS FOR CRACKING HYDROCARBON OILS TO PRODUCE LIGHT OILS

Original Filed June 28, 1920

UNITED STATES PATENT OFFICE.

GUSTAV EGLOFF AND HARRY P. BENNER, OF CHICAGO, ILLINOIS, ASSIGNEES TO UNIVERSAL OIL PRODUCTS COMPANY, OF CHICAGO, ILLINOIS, A CORPORATION OF SOUTH DAKOTA.

PROCESS FOR CRACKING HYDROCARBON OILS TO PRODUCE LIGHT OILS.

Application filed June 28, 1920, Serial No. 392,475. Renewed February 12, 1927.

Our invention relates to a process and apparatus for cracking heavy hydrocarbon oils by means of heat and pressure in a double high pressure still, and means of 5 internally heating same for the production of light oils characteristically gasoline, or the like.

Its salient objects are to provide a pressure distillation process for cracking 10 heavy hydrocarbon oils to produce light oils therefrom; to provide a process which may be operated continuously for the pressure distillation of heavy hydrocarbon oils to produce light oils therefrom by means of a 15 combustion chamber set within the body of the double high pressure still; to provide a process for the pressure distillation of heavy hydrocarbon oils to produce light oils therefrom by means of a double high pressure still and superheating the hydrocarbon vapors generated by one of said double high pressure stills; to provide a pressure distillation process for the heavy hydrocarbon oils to produce light oils, such as gasoline or 20 the like, from said heavy hydrocarbon oils by means of charging the lower of the double high pressure still and spraying untreated oil continuously over said oil while on pressure distillation; to provide 25 a process for the pressure distillation of heavy hydrocarbon oils to produce light oils therefrom by means of a double high pressure still in which both stills of said double high pressure still are charged with 30 said hydrocarbon oil to be treated, and continuously charging untreated oil to the system during pressure distillation.

The following is a description of an apparatus as shown in the drawing.

40 The numeral 1 represents a gas burner set in corrugated tube 2, which is within high pressure still 6. 2^a is a connection between corrugated tube 2 and corrugated tube 3 set in pressure still 5, to which tube 3 stack 4 is attached. A vapor line connects pressure still 5 through valve 8 and pipe 9 to dephlegmator 10 having baffle plates 11 set therein and provided with an inverted dish 12, and dephlegmated oil trap 13. The numeral 13^a, designates a dephlegmated oil or reflex return pipe attached to the lower part of still 6. The numeral 14 designates a vapor conduit connected with dephlegmator 10 in which con-

duit is placed valve 15. The pipe extension 55 15^a leads to condenser coil 16, set within water condenser box 17. The condensed pressure distillate oil passing through pipe 18 with uncondensable gas from condenser coil 16 passes to receiver 19. Pipe 20 is 60 attached to receiver 19 with pressure distillate control valve 21, having pipe 21^a connected with storage tank for pressure distillate oil. Pipe 23 is uncondensable gas line controlled by valve 22. Pipe 22^a is 65 connected to uncondensable gas tank. The numeral 24 represents pressure gage, and 24^a the gauge glass upon receiver 19. A raw oil pump 25, pumps raw oil via valve 26 and discharges through control valve 70 27, through preheater coil 28. A control valve 27 is used for passing raw oil through preheater coil 28 set in the path of combustion gases in flue 2^a. The preheated raw oil from coil 28 passes through pipe 29 set 75 in still 6, having perforations 30, through which the oil sprays into said still 6. The numeral 6^a represents nozzles which connect still 6 with still 5, being projected above the bottom of still 5. Insulating material 5^a surrounds stills 5 and 6. 31 is draw off pipe for residuum from still 6, controlled by valve 32, attached to pipe connection 33 with storage tank for said residuum oil.

One typical method of operation of this 85 process and apparatus when cracking a very refractory oil, such as steam still kerosene bottoms, Pine Island gas oil and the like, is to charge still 6 with one of said oils by means of raw oil pump 25, through coil 28 90 and pipe 29, or still 6 may be charged by way of residuum line 31, connected with valve 32 and pipe connections 33 by means of pump not shown. The pressure distillate control valve 21 and uncondensable gas valve 95 23 are closed. Valves 8 and 15 are opened. Burner 1 is ignited, the products of combustion passing corrugated tube 2, connections 2^a attached to corrugated tube 3, set in still 5, passing out of stack 4. The hydrocarbon 100 vapors generated in the system produce a generated pressure upon the entire system which is predetermined dependent upon the type of oil used. After the desired self-im-pressed pressure has been created in the sys-105 tem the operation may be continued under such pressure by suitably controlling the throttle valves 21 and 22 on the receiver 19.

- The hydrocarbon vapors generated in still 6 passing through pipes 6^a, connected to still 5 are superheated by the products of combustion, passing through corrugated tube 3. 5 The hydrocarbon vapors from still 5, passing through pipe 7, valve 8 and pipe 9, attached to dephlegmator 11 are fractionated, so that only the lighter vapors pass out through conduit 14, valves 15 and pipe 15^a to be condensed in condenser coil 16, running into receiver 19 when the system is on pressure distillation. The dephlegmated liquid condensed in dephlegmator 10 drops back in said dephlegmator to the trap 13, passing 15 down through pipe connections 13^a to the lower part of still 6. It is important to note in this pressure distillation process and apparatus that we do away entirely with furnace construction of brick work or like material. 20 We also do away with high furnace box construction which necessitates all construction work on pressure distillation processes being built 8 or 10 feet higher than our process and apparatus. We have found that this 25 cuts down the construction costs markedly and is an important feature of our process and apparatus. Our process and apparatus also economizes upon fuel consumption, as the products of combustion, pass through 30 the internal part of the still so that we do away with radiating heat from furnace walls and reduce heat loss to a minimum. Our stills are heavily insulated with magnesia, brick or kieselguhr. It is to be noted that 35 the products of combustion within the lower still pass on after giving up part of their heat content to the liquid in said lower still and superheat the vapors in the upper still, which then pass out through the dephlegmator. 40 We also have found that by preheating the raw oil fed into the system by means of waste products of combustion, that the capacity of the stills is increased.

- A typical operating run was to distil a 45 Pine Island gas oil of 31.0 Baumé gravity at a pressure of 125 pounds, producing therefrom 60 percent of a pressure distillate oil of 51.0 Baumé gravity containing therein 55 percent of a 57-58 Baumé gravity gasoline. 50 This yielded 33 percent of 57-58 Baumé gravity gasoline on the basis of oil used.

- The above is the preferred method of operation of this process and apparatus. However, when using easily crackable oils, such 55 as fuel oils, heavy residuums, heavy crude oils we may charge both stills with one of said oils and spray in raw charging oil into the upper still instead of the lower.

- We do not limit ourselves to any particular amount of still charge, because this is determined by the type oil which is to be cracked in our process. Nor does the type dephlegmator upon the system, as shown in drawing, act advantageously on all hydrocarbon oils. We have found that the char-

acter of the hydrocarbon oils profoundly modifies the type dephlegmating system necessary for cracking commercially.

We do not limit ourselves in this process to horizontal type stills but may utilize and believe it is within our disclosure to operate vertical and tube still arrangements.

We claim as our invention:

1. A process of treating hydrocarbon oil, consisting in charging the lower of a pair of superimposed stills with a bulk supply of oil, in passing the heating gases through a closed conduit located within said still, in passing the vapors generated in said lower still to the upper still wherein they are superheated by passing the combustion gases through a closed conduit located in said upper still, in continuously introducing a spray of preheated oil into said bulk supply of oil, in dephlegmating the vapors passing over from said upper still, in returning the reflux condensate resulting from such dephlegmation to said bulk supply of oil, in continuously withdrawing heavy residuum from said bulk supply of oil and in maintaining a superatmospheric vapor pressure on the oil undergoing conversion. 80 85 90

2. A process of treating hydrocarbon oil, consisting in charging the lower of a pair of interconnected stills with a bulk supply of oil, in heating the bulk supply of oil in said lower still by passing the heating gases through a closed conduit disposed therein, in passing the vapors generated from said bulk supply of oil to the upper of said pair of stills, and in there superheating the vapors by passing the combustion gases through a closed conduit disposed therein, in continuously introducing raw oil to said bulk supply of oil through a spray, in dephlegmating the vapors issuing from said upper still, and in condensing and collecting the resulting distillate. 100 105

3. A process for cracking petroleum oil comprising placing the oil to be cracked under pressure, initially passing the oil through an elongated conduit of restricted crosssection about which gases of combustion pass to impart heat to the oil, subsequently delivering the oil in the form of a spray to an enlarged zone wherein the oil spray is caused to directly contact with the exterior surface of a heating element, through which combustion gases of a higher temperature than the combustion gases passing about said conduit are flowing, in maintaining a pressure on the oil in such elongated conduit and in said enlarged zone in excess of 100 pounds per square inch in removing vapor generated from the oil and in subjecting such vapors to condensation and collection. 110 115 120

4. A process for cracking petroleum oil comprising placing the oil to be cracked under pressure, initially passing the oil through an elongated conduit of restricted 125 130

cross section about which gases of combustion pass to impart heat to the oil, subsequently delivering the oil in the form of a spray to an enlarged zone wherein the oil 5 is caused to flow from the exterior surface of a heating element, through which combustion gases of a higher temperature than the combustion gases passing about said conduit are flowing, in removing vapors generated from the oil as the result of said heat treatment and in passing such vapors in heat interchange relation with combustion gases which have been previously passed about said conduit, in thereafter subjecting the vapors to dephlegmation and condensation. 10
